UNITED STATES PATENT OFFICE

129,583

DESIGN FOR A COMBINED PROTRACTOR AND RULE

George S. Grant, Nashville, Ark.

Application July 1, 1941, Serial No. 101,846

Term of patent 7 years

To all whom it may concern:

Be it known that I, George S. Grant, a citizen of the United States, residing at Nashville, in the county of Howard and State of Arkansas, have invented a new, original, and ornamental Design for a Combined Protractor and Rule, of which the following is a specification, reference being had to the accompanying drawing, forming part thereof.

Figure 1 is a view in plan of a combined protractor and rule embodying my new design, and Figure 2 is a view in edge elevation.

I claim:

The ornamental design for a combined protractor and rule, as shown.
